UNITED STATES PATENT OFFICE.

JOHN C. BURNELL, OF CINCINNATI, OHIO, AND JOHN MEYER, OF COVINGTON, KENTUCKY.

DESIGN FOR A SIGN.

SPECIFICATION forming part of Design No. 16,743, dated June 22, 1886.

Application filed October 10, 1885. Serial No. 179,520. Term of patent 7 years.

To all whom it may concern:

Be it known that we, JOHN C. BURNELL and JOHN MEYER, the former of Cincinnati, in the county of Hamilton and State of Ohio, and the latter of Covington, Kenton county, Kentucky, have invented a new and useful Design for a Sign; and we do hereby declare the following to be a full, clear, and exact description of said invention, reference being had to the accompanying drawing, and to the letters or figures of reference marked thereon, which form a part of this specification.

The design consists of a truncated cone-shaped or longitudinally-rounded projection from a plane base, *d*, composed of annular walls divided into longitudinal sections representing staves *a a*, circular bands at a little distance from each other, representing hoops *b b*, and a circular end inserted within the walls and at a little distance from the outer

end of the walls, representing the head of a keg, all of which represents and configures a section of a keg, including the head, and not exceeding one-half the length of the keg, with its inner larger end affixed to a base, *d*. 25

What we claim is—

The design for a sign shown and described herein, consisting of a configuration and representation in alto-relievo of the end and surface of a cross-section of a keg or cask having 30 staves *a a*, hoops *b b*, and a head, *c*, affixed at its inner and larger end to a plane base or background, *d*.

In testimony whereof we affix our signatures in presence of two witnesses.

JNO. C. BURNELL.
JOHN MEYER.
